METHOD FOR ROUNDING THE SOLES OF SHOES

Corwin W. Baker, Beverly, Mass., assignor to
United Shoe Machinery Corporation, Flemington,
N.J., a corporation of New Jersey

Application February 12, 1949, Serial No. 76,043

3 Claims. (Cl. 12—142)

1

This invention relates to methods of sole rounding, and is illustrated herein with reference to a machine of the type disclosed in United States Letters Patent No. 1,030,606, granted on June 25, 1912, upon an application of F. H. Perry. Machines of this class are commonly employed for trimming the edge of a shoe sole, after it has been laid and temporarily secured to the shoe bottom, preparatory to the outsole stitching operation.

The principal operating tool of this type of machine consists of a chopping knife which is rapidly reciprocated as the shoe is fed past it to make a series of overlapping cuts along the desired outline of the sole edge and directed across the latter from the bottom of the sole through the upper margin thereof. The shoe is supported against the thrust of the knife by a feeding member, commonly called a feed point, which enters the welt crease and engages the upper margin of the sole or welt opposite to the knife. When the machine is in proper adjustment the knife and feed point just meet at the end of the cutting stroke of the knife.

However, all the cutting strokes of the knife are not of precisely the same length because of the slack in the joints of the driving mechanism resulting from the usual bearing clearances, and the wear which accompanies the ordinary use of the machine.

Consequently, the knife, from time to time, will engage the feed point making a shallow indentation therein. This tends to dull the knife. Upon being dulled, the effectiveness of the knife is diminished not only for this reason, but also because the knife is shortened, causing the rounding cut to be incomplete at the upper margin of the sole. Thus, until the knife is resharpened and readjusted, there may be a thin fringe or projection extending from the upper ridge of the sole edge at various points along it which should be trimmed therefrom in order that the proper guidance of the shoe during the outsole stitching operation will not be disturbed.

In view of the foregoing, the object of the present invention is to obtain a complete severance of the sole without leaving any fringe or other undesirable projection upon the sole edge, and also without necessitating the engagement of a knife with any support or other machine part, whereby any undue wear of the knife, and the abovementioned difficulties arising therefrom, are avoided.

With the first of the above-mentioned objects in view, the invention provides an improved method of rounding soles which consists in making an incision in the upper margin of the sole along the desired outline of the sole edge, and making a second cut, along the same outline, directed from the bottom of the sole toward the upper margin thereof, the above-mentioned incision and cut each being of such depth that

they open into each other but do not pass completely through the sole. It is apparent that the practice of this method insures a flat and continuous cut across the sole edge from one side to the other, as well as the complete severance of the excess sole material from the shoe, because one cut is made from each side of the sole into the other along the same line. Similarly, there is eliminated any problem in regard to making either cut of such depth that it passes entirely through the sole material without being carried into engagement with whatever means or member is used for supporting the work. In accordance with a further feature of the invention, the above method may have as an additional step that of supporting a limited length of the upper margin of the sole extending from the beginning of the incision made therein along each side of it. Such support for the sole edge insures against any deformation being made in the upper margin of the sole along the incision particularly when, as in the present case, the incision is made by a draw cut.

Invention is also to be recognized in an improved sole rounding mechanism to be described later for purposes of explaining the practice of the above method. However, this mechanism is not to be claimed herein, but forms the subject-matter of my application Serial No. 210,395, filed on February 10, 1951, a division of this application.

The above and other features of the invention will now be described in detail with reference to the illustrative machine shown in the accompanying drawings, and will be defined in the claims.

In the drawings,

Fig. 1 is a side elevation of a portion of the head of a rounding and channeling machine embodying the invention;

Fig. 2 is a sectional plan view, the section being taken horizontally at the level of the chopping knife through the sole and the feed point; and

Fig. 3 is a rear elevation of the feed point, illustrating the relation of the spur thereon and the rounding cut made upon the sole.

In the illustrated machine, which is the same as the above-mentioned Perry machine except as will be specifically pointed out below, 10 indicates the continuously reciprocating chopping knife, 12 the knife carrier, 14 the slideway in which the carrier moves horizontally, 16 the bottom rest, 18 the oscillating support for the bottom rest, 20 the feed point, 22 the crease guide, and 24 the forepart guide. As usually constructed, the feed point has set into its rearward side a work engaging plate 26 which is positioned on the feed point by dowels 28 and is secured thereto by a screw 30.

The novel structure provided by this invention consists of a cutter in the form of a spur

32, which extends rearwardly of the machine from a plate 34 which is let into the lower serrated work engaging surface of the feed point flush therewith. As shown in Fig. 3, the spur has the shape of a slim wedge, its cutting edge being disposed at the right hand side of the feed point, facing toward the right (in the direction of the return stroke of the feed point) and at the level of the chopping knife 10.

The operating characteristics of the machine will now be briefly summarized, but only to the extent necessary for an understanding of the present invention.

The bottom rest 16 is adapted to seat upon the bottom of a shoe S and hold the latter with the upper margin of the sole against the crease guide 22 or feed point 20, both of which extend into the welt crease of the shoe. The bottom rest 16 and feed point 20 are oscillated together from right to left (when the machine is viewed from the front) to impart a feeding movement to the shoe, and during the remainder of one cycle of operation are returned to their original positions at the right hand ends of their strokes. The operation of the continuously reciprocating chopping knife 10 is so timed that its cutting stroke, directed toward the feed point, terminates when the feed point is at the mid point of its return stroke. At this time the return stroke of the feed point is momentarily interrupted, and the feed point is quickly reciprocated toward and away from the bottom rest so that the thrust of the knife upon the shoe, formerly taken by the crease guide, is resisted by the feed point when the sole is cut by the chopping knife. Thus, during each part of the return stroke of the feed point 20 its sole engaging surface is flush with or very slightly forward of that of the crease guide, whereby back feeding action of the feed point during its return stroke is avoided.

In the above-mentioned Perry machine the chopping knife, corresponding to the knife 10 disclosed herein, is so adjusted in the carrier that it just meets the feed point at the end of its cutting stroke. In the present machine on the other hand, the chopping knife 10 is so adjusted on the carrier 12 that its cut extends well into the sole, but not through the upper margin thereof. That is, the chopping knife 10 at the end of its cutting stroke stops in proximity to the plate 34 and out of engagement therewith, as illustrated in Fig. 2. It is now evident that the knife in the present machine is not subject to becoming dulled by engagement with the feed point or any part thereof.

The severance of the chip C (Fig. 3) which is outside of the desired outline O of the rounded sole edge, is completed by making another cut along the same outline directed from the upper margin of the sole toward the bottom thereof, these two cuts being of such depth that each opens into the other. This cut or incision made into the upper margin of the sole is produced, in the operation of the illustrated machine, by the spur 32 which, as stated above, is disposed at the level of the knife, and also is offset slightly to the right of the knife so that any interference between them is avoided.

To summarize my improved method and the operation of the machine, the shoe S is presented to the machine in the usual way with its bottom resting upon the bottom rest 16, and with the crease guide 22 and feed point 20 extending into the welt crease, the shoe being positioned vertically with respect to the chopping knife 10

by either the crease guide or the forepart guide 24 in a manner which is well understood in this art. One cut into, but not through the sole is made by the rapidly reciprocating chopping knife which makes a series of overlapping cuts, along the desired outline of the sole edge, extending from the shoe bottom toward the upper margin of the sole. Each cutting stroke of the chopping knife occurs between successive feeding strokes of the feed point and bottom rest, and also during the interruption in the return stroke of the feed point. A second cut in which the severance of the chip C from the shoe is completed, is made during each part of the return stroke of the feed point by the spur 32, this being a draw cut in the upper margin of the sole, which, like each cut made by the chopping knife, extends along the desired outline of the rounded sole edge. The incision made by the spur 32 is also made slightly in advance of the path of the knife 10 and is of such depth that the cutting edge of the knife enters into it near the end of each cutting stroke.

Although the feed point does not bear upon the upper margin of the sole with any appreciable force during its return stroke, the sole margin is substantially in engagement with the feed point at this time. Accordingly, the plate 34 is in such a position that it supports a limited length of the upper margin of the sole immediately adjacent to the incision made by the spur, and thus insures against any deformation of the upper margin of the sole as a result of the cutting action of the spur.

Having thus described my invention, what I claim as new and desire to secure by Letters Patent of the United States is:

1. That improvement in methods of rounding soles which consists in alternately making an incision in one side of a sole by a draw cut extending along the desired outline of the sole edge, and completing the severance of the sole by making another cut along said outline directed from the other side of the sole into the incision.

2. That improvement in methods of rounding soles which consists in making an incision in the upper margin of a sole along the desired outline of the sole edge, supporting a limited length of the said upper margin along each side of the said incision from the beginning thereof, and completing the severance of the sole by cuts directed from the bottom thereof into the said incision.

3. That improvement in methods of rounding soles which consists in making an incision in the upper margin of a sole by a draw cut directed along the desired outline of the sole edge, and completing the cut through the sole by a succession of chopping cuts extending from the bottom of the sole into the said incision.
